A. POLLAK.

LEAD PENCIL.

APPLICATION FILED FEB. 2, 1921.

1,391,273.

Patented Sept. 20, 1921.

UNITED STATES PATENT OFFICE.

ABRAHAM POLLAK, OF NEW YORK, N. Y., ASSIGNOR TO SAMUEL KANNER, OF NEW YORK, N. Y.

LEAD-PENCIL.

1,391,273.

Specification of Letters Patent. Patented Sept. 20, 1921.

Application filed February 2, 1921. Serial No. 441,739.

To all whom it may concern:

Be it known that I, ABRAHAM POLLAK, a citizen of the United States, and a resident of New York city, in the county of New York and State of New York, have invented certain new and useful Improvements in Lead-Pencils, of which the following is a specification.

The invention relates to improvements in mechanical lead pencils, and consists in the novel features hereinafter described, and particularly pointed out in the claims.

The lead pencil of my invention comprises an outer barrel portion, a head on the outer end thereof, a conical tip on the inner end thereof, an internally threaded nut within the inner end portion of said tip, a longitudinally movable screw engaged by said nut and having a point to engage the inner end of the lead and at its opposite end a guiding head, a sleeve of special construction within the outer barrel of the pencil and affording spaces to receive leads and also guides for the head on the screw, and a clutch sleeve within the tip member of the pencil, adapted to receive the lead and to grip the same when the lead is propelled forwardly for writing purposes. The outer barrel of the pencil and the tip portion thereof are relatively rotatable, one being held stationary while the other is rotated for effecting the travel outwardly or inwardly of the confined screw. The several parts of the lead pencil have special features of advantage both as to operation, manufacture and assembly. The main object of the invention is to produce a new construction of mechanical lead pencil which shall be entirely efficient and properly withstand the usual treatment to which lead pencils are subjected.

The invention will be fully understood from the detailed description hereinafter presented, reference being had to the accompanying drawings, in which:

Figure 1 is a central longitudinal section through a lead pencil embodying my invention;

Fig. 2 is a vertical transverse section, on an enlarged scale, through the same taken on the dotted line 2—2 of Fig. 1;

Fig. 3 is a corresponding section through the same taken on the dotted line 3—3 of Fig. 1;

Fig. 4 is a corresponding section through the same taken on the dotted line 4—4 of Fig. 1;

Fig. 5 illustrates the outer head of the pencil and a tube connected therewith and constituting a holder for leads and for a projecting piece of rubber serving as an eraser;

Fig. 6 is a top view of the sleeve fitting within the outer barrel of the pencil;

Fig. 7 is a detached elevation of the clutch member of the pencil;

Fig. 8 is a longitudinal section, partly broken away and on an enlarged scale, of the same;

Fig. 9 is a detached side elevation of the tip member of the pencil, and

Fig. 10 is a side elevation of the pencil.

In the drawings, 15 designates the exterior plain tubular barrel of the pencil, 16 the tip member at one end of said barrel, and 17 an ornamental head at the other end of the barrel carrying a tube 18 which may be slid within the barrel 15, as shown in Fig. 1, and is adapted to hold leads in reserve and also an eraser 19 whose end will project outwardly beyond the tube 18, as shown. I will make use of the tube 18 only when the pencil is to be of sufficient length to permit me to do so, and on other occasions the tube 18 will be omitted and the barrel 15 will be shortened accordingly, and the head 17 will be applied upon the outer end of the shortened barrel.

The tip-member 16 has a reduced inner end portion 20 which enters the barrel 15 and also an internally threaded section 21 which receives a nut 22 screwed into said section 21, said nut 22 having an interior threaded bore and also, at its forward end, a central recess 23 which is in effect an enlargement of said bore. The tip-member 16 has the usual opening for the piece of marking lead 24 and contains a clutch-tube or sleeve 25 separately shown in Figs. 7 and 8 and which is tapered, at its forward end, as at 26, to engage the inner tapered walls of the tip-member 16, and at its rear end said clutch-tube or sleeve 25 is entered within the recess 23 of the nut 22. The clutch-tube or sleeve 25 is in one continuous piece and at its forward tapered end is slotted, as shown in Figs. 7 and 8, to afford gripping

fingers for holding the lead 24 against slipping from the lead pencil and also against looseness when the pencil is in use.

Within the barrel 15 is located a close-fitting sleeve 27 which is formed from sheet metal and subdivided at its central portion by a long U-shaped section 28 between the sides of which and the sides of the sleeve are formed chambers 29 which may be utilized 5 as reservoirs for holding leads, the formation of the sleeve 27 being more particularly shown in Figs. 2 and 6. The sleeve 27 is bifurcated at its forward end, as at 30 (Fig. 6), to form two side members which 10 are conceavely grooved, as at 31, and are adapted to have a limited spring action adapting them to return to their initial position when they are sprung outwardly in a direction from each other. The sleeve 27 15 is formed from a sheet of metal bent to the form indicated in Fig. 2 and the edges of said sheet metal are separated or spaced apart adjacent to the U-shaped section 28, and at the rear end of said section 28 the 20 material of the sleeve is cut and bent to form inwardly extending fingers 32 which overlap each other and cross one edge of the space between the two sides of the section 28 so as to form a stop at the rear end of 25 said sleeve 27 for arresting the head 33 secured on the rear end of the screw 34 when said screw is worked inwardly to the full limit of its movement. The forward members of the sleeve 27, and which for convenience I will number 35, are adapted to 30 be sprung upon the threaded section 21 of the tip-member 16, which tip-member is formed at the forward end of said section 21 with an annular groove 36 adapted to 35 receive the inwardly pressed or concaved portions 31 of the members 35, as shown in Fig. 1. The pressure of the members 35 against the tip-member 16 and the engagement of the grooved forward ends of said 40 members 35 with the annular groove 36 of said tip-member serve to lock the tip-member and sleeve 27 in proper end relation to each other. The tip-member 16 is formed with an annular shoulder 37 which abuts 45 against the forward edge of the barrel 15.

The worm or screw 34 carries the transversely elongated head 33 at its rear end and at its forward portion is within the co-operating nut 22 and has a plain forward 50 rod member 38 of about the diameter of the lead 24 and adapted, at the proper time, to propel the lead through the clutch sleeve 25 and tip-member 16, as will be understood on reference to Fig. 1. The screw 34 engages the interior thread of the nut 22 and at its forward portion passes freely within the rear end of the clutch-sleeve 25. The elongated head 33 on the rear end of the screw 34 lies between the sides of the U-shaped section 28 of the sleeve 27 and said

sides serve to guide said head during the travel of the screw 34 and also to impart rotary movement to said head and through said head to the screw 34, whereby said screw is by said nut compelled to travel either forwardly or rearwardly in accordance with the direction of rotation of the barrel 15 and sleeve 27. 70

The nut 22 when screwed home within the rear end of the tip-member 16 becomes rigid, and hence when the screw 34 is caused to rotate by the turning of the barrel 15, said screw is compelled to travel in one direction or the other in accordance with the direction of rotation of said barrel. The sleeve 27 so tightly fits the barrel 15 that it will rotate therewith, and therefore when the barrel is rotated, the rotation of the sleeve causes the sides of the U-shaped section 28 to act through the elongated head 85 33 and turn or rotate the screw 34.

When the parts are assembled in the relation shown in Fig. 1, the forward end of the barrel 15 covers over the sleeve members 35 and the adjacent portions of the tip-member 16 and in this assembled relation the tip-member 16 cannot be pulled out from the remaining portion of the pencil, since at that time the walls of the forward end of the barrel 15 will prevent the inwardly recessed portions 31 of the sleeve 27 from coming out of the annular groove 36 of the tip-member 16. The sleeve 27 when rotated by the barrel 15 may turn upon the inner or rear end of the tip-member 16, while said member is held stationary, the groove-portions 31 of the sleeve 27 then turning within and around the annular groove 36 of said tip-member. 95

The lead 24 will be inserted into the forward end of the tip-member 16 and into the clutch-tube or sleeve 25 by hand, the screw 34 having previously been caused to recede rearwardly by the rotation of the barrel 15 and sleeve 27. When it is desired to project the lead 24 for writing purposes, the user will hold the tip-member 16, in, say, the left hand and with the right hand rotate the barrel 15 in a direction to cause the screw 34 to move forwardly 105 against the lead and project the same to the desired extent. After the use of the pencil for writing purposes has ceased, the writer will hold the tip-member 16 stationary and reversely rotate the barrel 15 for retracting the screw 34, and thereupon the writer will push the lead 24 back into the tip-member 16 and clutch-sleeve 25 by hand. If the user should prefer he may actuate the screw 34 by holding the barrel 15 stationary and 110 rotating the tip-member 16 and with it the nut 22, to cause a direct traveling action in the screw 34, but ordinarily the method of operation would be to hold the tip-member stationary and rotate the barrel 15. 115

- In assembling the parts of the pencil, the tip-member 16, clutch sleeve or tube 25 and nut 22 will first be brought together, and then the forward end of the sleeve 27 will be 5 passed upon and engaged with the rear end of the tip-member, the forward end of the U-section 28 affording a stop to abut against the tip-member and arrest the sleeve when it has reached its proper position on the tip- 10 member, and thereupon the sleeve 27 and the rear end of the tip-member will be pushed into the barrel 15. The sleeve 27 is slightly contractible around its circumference due to its opposite edges being spaced 15 from the curved part of the section 28 (Fig. 2), and hence may be squeezed into the barrel 15, which the sleeve will tightly bind. The formation of the sleeve 27 is shown in Figs. 2 and 6, in which it may be noticed 20 that the sleeve has two extended segmental sides to engage with a spring action the walls of the barrel 15 and the inner U-shaped section 28 whose sides aid in keeping said segmental sides firmly against said 25 walls while at the same time serving as means to turn and guide the head 33 and create, with said segmental sides, pockets 29 which may, if desired, be utilized to hold reserve leads. 30 In the operation of the pencil the clutch-sleeve or tube 25 performs special duties. The forward split and tapered end of the tube 25 is arranged to initially loosely engage the inner tapered forward walls of the 35 tip-member 16 and the rear end of said tube is freely and slidably supported in the recess 23 formed in the stationary nut 22, and said tube is thus capable of a limited sliding action which results in the following 40 conditions: When the screw 34 is in its rear position and a piece of lead 24 is introduced to the tube 25 through the front end of the tip-member, the lead moving against the tube will slide the same rearwardly as far 45 as the end of the recess 23 will permit and this affords freedom to the clutch-fingers at the front end of the tube and the inward movement of the lead is thereby facilitated, and when the rod 38 of the screw 34 is 50 moved forwardly against the lead to project the same for writing purposes, the forward pressure exerted by that act against the tube 25 drives the tapered end of the tube against the adjacent walls of the tip-member 16 with 55 the result that the lead becomes firmly clutched and incapable of any axial rotation during its use for writing purposes.
- What I claim as my invention and desire to secure by Letters Patent, is:
- 60 1. In a pencil, an exterior barrel, a hollow tip-member whose rear end portion is within the forward end of said barrel and provided with an annular groove, a longitudinal sleeve within said barrel and having 65 forwardly projecting arms engaging the sides of the rear end of said tip-member and formed with depressions to lie within said annular groove, an internally threaded nut confined within said tip-member, a clutch-sleeve for leads within said tip member, a longitudinal screw-passing through said nut and entering said clutch-sleeve for projecting the lead therefrom, and means within said sleeve for guiding said screw and holding the same against rotation except therewith, said barrel and sleeve being rotatable for rotating said screw. 70
2. In a pencil, an exterior barrel, a hollow tip-member whose rear end portion is within the forward end of said barrel and provided with an annular groove, a longitudinal sleeve within said barrel and having forwardly projecting arms engaging the sides of the rear end of said tip-member and formed with depressions to lie within said 75 annular groove, an internally threaded nut confined within said tip-member, a clutch-sleeve for leads within said tip-member, a longitudinal screw-passing through said nut and entering said clutch-sleeve for projecting the lead therefrom, means slidably connecting the screw with said sleeve and means for rotating said sleeve and therewith said screw. 80
3. In a pencil, an exterior barrel, a hollow tip-member whose rear end portion is within the forward end of said barrel and provided with an annular groove, a longitudinal sleeve within said barrel and having forwardly projecting arms engaging the 85 sides of the rear end of said tip-member and formed with depressions to lie within said annular groove, an internally threaded nut confined within said tip-member, a clutch-sleeve for leads within said tip-member, a longitudinal screw-passing through said nut and entering said clutch-sleeve for projecting the lead therefrom, means slidably connecting the screw with said sleeve and means for rotating said sleeve and therewith said screw. 90
3. In a pencil, an exterior barrel, a hollow tip-member whose rear end portion is within the forward end of said barrel and provided with an annular groove, a longitudinal sleeve within said barrel and having forwardly projecting arms engaging the 95 sides of the rear end of said tip-member and formed with depressions to lie within said annular groove, an internally threaded nut confined within said tip-member, a clutch-sleeve for leads within said tip-member, a longitudinal screw-passing through said nut and entering said clutch-sleeve for projecting the lead therefrom and having a laterally projecting head on its inner end and a smooth rod on its forward end to engage 100 the lead, means on said sleeve engaging said head and adapted on the rotation of said sleeve to rotate said head and therewith said screw, and means for rotating said sleeve. 105
4. In a pencil, an exterior barrel, a hollow tip-member whose rear end portion is within the forward end of said barrel and provided with an annular groove, a longitudinal sleeve within said barrel and having forwardly projecting arms engaging the 110 sides of the rear end of said tip-member and formed with depressions to lie within said annular groove, an internally threaded nut confined within said tip-member, a clutch-sleeve for leads within said tip-member, a longitudinal screw-passing through said nut and entering said clutch-sleeve for projecting the lead therefrom and having a laterally projecting head on its inner end, 115 opposite side walls connected with said 120
- 65 125
- 65 130

sleeve embracing said head and serving when the sleeve is rotated to guide and rotate said head and therewith said screw, and means for rotating said sleeve.

- 5 5. In a pencil, an exterior barrel, a hollow tip-member whose rear end portion is within the forward end of said barrel and provided with an annular groove, a longitudinal sleeve within said barrel and having forwardly projecting arms engaging the sides of the rear end of said tip-member and formed with depressions to lie within said annular groove, an internally threaded nut confined within said tip-member, a clutch-sleeve for leads within said tip-member, a longitudinal screw-passing through said nut and entering said clutch-sleeve for projecting the lead therefrom and means within said sleeve for guiding the inner 10 end of said screw, said tip-member and nut and said sleeve being relatively rotatable for actuating said screw.
6. In a pencil, an exterior barrel, a hollow tip-member whose rear end portion is within the forward end of said barrel, an internally threaded nut confined within said tip-member, a clutch-sleeve whose forward end engages the inner walls of the forward end of said tip-member and whose rear end 15 is supported and centered by said nut, a longitudinal screw passing through and engaging said nut and entering said clutch sleeve for projecting the lead therefrom, and means within said barrel for guiding the rear end of said screw when said screw is actuated by said nut on the rotation of said barrel or of said tip-member.
7. In a pencil, an exterior barrel, a hollow tip-member connected therewith having 20 inwardly contracted inner surfaces at its forward end and a fixed member at its rear

end containing an opening for a screw-rod and concentric therewith a shallow recess, a clutch-tube having a tapered slotted forward end adapted to said surfaces of the tip-member and its rear end supported freely in said recess, whereby said tube is rendered capable of limited sliding movement, a screw-rod operable through said fixed member and within said tube for projecting the marking lead, and means for effecting the longitudinal travel of said rod.

8. In a pencil, an exterior barrel, a hollow tip-member whose rear end is within the forward end of said barrel and around which said barrel is rotatable, a longitudinal sleeve within said barrel and tightly engaging the same and interlocked with the rear end of said tip-member and rotatable with said barrel around the same, 25 an internally threaded nut at the rear end of said tip-member and rigid therewith, a clutch-tube for leads within said tip-member, and a longitudinal screw-rod passing through said nut and entering said clutch-tube for projecting the lead therefrom and having a head on its rear end, said sleeve being formed of sheet metal and having segmental sides engaging the inner walls of said barrel and a transverse U-shaped section between which and said sides are formed pockets and between the sides of which section the head of said screw-rod is confined and guided, and the longitudinal edges of said segmental sides being spaced 30 apart to allow a spring action in said sides against the inner walls of said barrel.

Signed at New York city, in the county of New York and State of New York, this 28th day of January, A. D. 1921.

ABRAHAM POLLAK.
